UNITED STATES PATENT OFFICE.

WILLIAM THOMAS, JR., OF LOS ANGELES, CALIFORNIA, ASSIGNOR TO THOMAS AUTO TRAFFIC SIGNAL COMPANY, OF LOS ANGELES, CALIFORNIA, A CORPORATION OF CALIFORNIA.

DESIGN FOR A TRAFFIC SIGNAL.

Application filed April 18, 1922. Serial No. 1,831. Term of patent 14 years.

To all whom it may concern:

Be it known that I, WILLIAM THOMAS, Jr., a citizen of the United States, residing at Los Angeles, in the county of Los Angeles and State of California, have invented a new, original, and ornamental Design for a Traffic Signal, of which the following is a specification, reference being had to the accompanying drawing, forming a part thereof.

Figure 1 is a plan view of a traffic signal. Fig. 2 is a front view of the same showing my new design.

I claim:

The ornamental design for a traffic signal as shown.

WILLIAM THOMAS, JR.
